METHOD OF AND APPARATUS FOR MAKING
PRINTING PLATES

Joseph Schwartz, Philadelphia, Pa., and Amos Ackley, Camden, N. J., assignors to Westcott & Thomson, Inc., Philadelphia, Pa., a corporation of Pennsylvania

Continuation of application Serial No. 586,264, January 13, 1932. This application April 27, 1936, Serial No. 76,674

3 Claims. (Cl. 22—200)

Our invention is an improved method of and apparatus for making printing plates, and the leading objects of our invention are to eliminate or minimize the blow holes commonly resulting from the trapping of gases in the solidifying molten material or type metal, to avoid the necessity for shaving or trimming the back of the printing plate, and to provide a printing plate with printing characters having sharp outlines and a solid body. In accordance with our invention, we suck out of the molten metal, through porous surfaces at one or both sides of the mold used for casting the plate, the gas bubbles forming, segregating, or otherwise entrapped in the metal, thus preventing the formation of blow holes in the plate and improving its solidity, strength, and sharpness of printing characters. Other features and advantages of the invention will appear from the following description of a species or form of embodiment, and from the drawing.

This application is a continuation of our pending application Serial No. 586,264, filed January 13, 1932, as to common subject matter.

In carrying out our invention as here illustrated and as described in detail hereinafter, the molten type metal for forming a printing plate is poured between a front matrix or intaglio sheet and a heat insulating backing sheet spaced therefrom and preferably formed of fibrous material. These inner matrix and insulating sheets are suitably positioned relatively to one another by the bed or front plate and cover or back plate of a casting box,—against which plates the matrix and insulating sheets may be firmly and uniformly held as a result of the suction or exhaustion of air through a multiplicity of small apertures formed in such plates, and covered by the matrix and insulating sheets. By sufficiently energetic suction through the perforated or foraminous plate(s) as just described, bubbles of gas in the molten material, which might otherwise remain entrapped therein and form blow-holes in the solidified printing plate, are sucked out through either or both of said sheets, which line the aforesaid foraminous wall structure of the mold,—either or both being of sufficiently permeable or porous character. In many cases, it is desirable to make the matrix sheet of close-textured, relatively impermeable pressed paper stock, and to draw or suck off the gases mainly through a more porous backing sheet. The front and back plates are preferably provided with unpolished or frictional surfaces so that there can be no slippage of the matrix or insulating sheet

relatively to the plates, and suction is so uniformly applied to the backs of the matrix and the insulating sheet as to hold them against wrinkling or contraction as a result of contact of the liquefied type metal therewith or of the cooling of such metal. The sheets are held by suction at so many different points that the stresses are uniformly distributed throughout the entire area of the sheets, without any tendency to tearing.

The insulating backing sheet is preferably composed of fibrous material, such as paper, which is incombustible at the melting point of type metal, has a smooth surface, and is of sufficient porosity. Thus the surface of the cooling type metal has little or no tendency to slip thereon. No. 1 jute paper about 10/1000 in. thick has been found very satisfactory, though any stout paper such as above indicated will answer the purpose. To draw off gas bubbles through such a sheet effectively, a degree of suction or partial vacuum materially in excess of what would be necessary merely to hold the sheet firmly in place is needful: e. g., a partial vacuum corresponding to some 7–15 in. of mercury,—10 in. representing a fair mean,—as against a mere 1 or 2 in. suction required to hold a sheet against the mold plate. The insulating sheet such as above indicated has characteristics similar to that of the matrix or intaglio sheet when the latter is composed of a plastic porous pulp or paper sheet having characters impressed therein, and then hardened. (This is more porous than the dense-pressed matrix hereinbefore referred to.) By using insulating sheets of different thicknesses, printing plates of different thicknesses may be cast from the same matrix, or from matrices of like thicknesses.

In carrying out our invention in casting a printing plate, the molten type metal is poured between parallel walls, consisting of the matrix and insulating sheets, which have substantially the same temperature and characteristics, and hence the type metal is permitted to cool naturally without sudden and unequal chilling of different surfaces or parts thereof, and the bubbles of gas or air which are entrapped or formed in the metal are sucked out. Since the matrix and insulating sheets are held by the suction firmly, and without wrinkling, contracting, or tearing, against the frictional surfaces of the apertured plates, the usual shrinkage of the printing plate in cooling is minimized. The back of the printing plate has a smooth, uniform surface, suitable for use without shaving. The exhaustion of air

through the matrix (when the latter is sufficiently porous), as well as through the backing sheet, prevents any air being trapped in the intaglio characters by the rising metal. The characters are sharp in outline and free from blow holes.

In the drawing, Fig. I is a front elevation of apparatus embodying our invention and adapted for the practice of our improved method.

Fig. II is a top plan view of the casting box 10 with the cover open.

Fig. III is a top plan view of the casting box with the cover closed; and

Fig. IV is a transverse sectional view on an enlarged scale taken through the bed, matrix, 15 plate of type metal, insulating sheet, and cover, in the plane indicated by the line IV-IV of Fig. III.

In the embodiment of our apparatus illustrated in the drawing, a supporting base 1 has fixed thereto a plate 2 forming an end closure for a hollow casting box 3 provided with a concave wall 4 adapted to form a bed or front. The lower unpolished portion of the wall 4, adapted to form a frictional seat for a matrix 5, is provided with numerous apertures or perforations 6, preferably of small cross section and comparatively closely spaced, and communicating with the suction chamber 7 of the box 3. The suction chamber 7 communicates through a suitable tube 8 with the exhaust side of a pump 9, which may be driven from any suitable source of power, such as the electric motor 10. The operation of the exhaust pump creates a vacuum in the chamber 7, which results in the matrix 5 being held at a great number of points securely and uniformly against the surface of the bed by atmospheric pressure.

A door or closure 11 is hinged to the casting box 3 and has an unpolished convex wall 12 forming 40 a frictional core complementary to the bed formed by the wall 4 and having a tapered top 13 providing a mouth for receiving the casting metal when the door or back 11 is closed.

The wall 12 contains apertures 14, which are 43 preferably of small cross section and closely spaced and which communicate with the vacuum chamber 15 in the cover 11. The chamber 15 communicates through a tube 16 with the exhaust side of the pump 9, the operation of which causes 50 a heat insulating backing sheet 17 to be drawn toward and held tightly against the wall 12 at a great number of points. Any tendency of the sheet 17 to slip or wrinkle is therefore resisted over substantially the entire area, and the resulting stresses are so distributed as to avoid tearing the sheet.

The cover may be held in desired closed relationship to the box by a latch 18 on the box coacting with a boss or stud 19 on the cover.

60 In accordance with our invention, the air is exhausted by the pump 9 from the chambers 7 and 15; the matrix 5 is seated in the box with its back in contact with the perforated surface of the wall 4; and the heat insulating sheet 17 is applied to the convex perforated wall or core 12.

The cover is then closed and latched and molten type metal poured into the mouth formed be-

tween the tapered surface 13 and the upper unperforated portion of the concave wall of the casting box; the suction on the matrix and insulating sheet being meanwhile maintained. The type metal flows downward between the matrix 5 and insulating sheet 17 to form a printing plate 20, which cools and hardens gradually and uniformly due to the similarity of temperature and characteristics of the surfaces of the matrix and sheet with which it contacts. The matrix and insulating sheet are prevented from slipping or shrinking by the suction uniformly applied to their back surfaces, and resist or minimize the shrinkage of the printing plate 20 during cooling, since the metal interlocks with the intaglio recesses of the matrix and in the pores and on the filaments of the insulating sheet, which is prevented from tearing or wrinkling by the uniform distribution over the entire area thereof of the stresses communicated thereto. As already 20 mentioned, gases are drawn out of the molten metal through one or both of the sheets 5 and 17, preventing the formation of blow holes and assuring a solid, uniform structure of the metal when solidified. When the inner (matrix and 25 backing) sheets 5, 17 are removed from the mold box along with the cast printing plate 20, air drawn through the holes 6 and 14 by the exhaust pump 9 serves to cool the mold walls 4 and 12, until the sheets 5, 17 are replaced, or the pump 30 30 is stopped.

Plates can be cast as thin as would normally be desired without risk of having blow holes therein, and of unvarying standard thickness, so that the usual shaving of their back is unnecessary.

Having thus described our invention, we claim:

1. An improved method of casting a printing plate in a mold comprising front and back walls, with a porous inner sheet lining at least one of said walls and in contact with the molten plate material when the latter is poured in the mold; which method comprises sucking gas bubbles out of said molten plate material, poured as aforesaid, through the porous sheet lining aforementioned, under a suction sufficient to prevent the formation of blow-holes and assure a solid, uniform structure of the cast plate.

2. A method in accordance with claim 1, particularly characterized in that while the front mold wall has a matrix, the gas bubbles are sucked out through a porous inner sheet lining the back mold wall.

3. An improved apparatus for casting printing plates comprising a mold having front and back walls, at least one of them foraminous, a porous inner sheet lining for the said foraminous wall structure of said mold, and means for exerting, through the foraminous wall structure and the said porous sheet lining, a suction sufficient to draw off through said lining the gas bubbles in the molten plate material poured in the mold, thereby preventing the formation of blow holes and assuring a solid, uniform structure of the cast plate.

JOSEPH SCHWARTZ.
AMOS ACKLEY.
